UNITED STATES PATENT OFFICE.

ALFRED WILBUR, OF ALLEGHENY, PENNSYLVANIA.

FLANGING-MACHINE.

SPECIFICATION forming part of Letters Patent No. 276,111, dated April 17, 1883.

Application filed March 20, 1882. (No model.)

To all whom it may concern:

Be it known that I, ALFRED WILBUR, of Allegheny city, in the county of Allegheny and State of Pennsylvania, have invented a new and useful Improvement in Flanging-Machines; and I do hereby declare the following to be a full, clear, and exact description thereof, reference being had to the accompanying drawings, forming a part of this specification, in

10 which—

Figure 1 is a vertical central section of my improved flanging-machine, part being shown in full lines. Fig. 2 is a detached view of the flanging-head in section and the shaft and 15 sleeve on which it is supported in full lines. Fig. 3 is a side view of the flanging-head, and Figs. 4 and 5 are bottom views of flanging-heads of irregular shapes.

Like letters of reference indicate like parts 20 in each.

My invention relates to machines for forming what are termed "inside flanges" on boiler-heads and like plates of metal, such as flanges around flue holes. These machines are 25 generally formed of a cage having an annular former at its base, a flanging-head supported on a shaft extending up through the cage, and mechanism for drawing the head up within the former, the plate to be flanged being placed 30 over the head and its shaft and under the annular former, and the head being drawn by means of its shaft through the hole in the plate and bending the flange up against the annular former. The principal object of my 35 invention is to improve the construction of these machines in certain particulars, and so render their operation more perfect, and enable them to form more evenly bent and truer flanges, as well as to form flanges around ir- 40 regularly-shaped holes, such as man-holes and flue-holes having other than circular form.

My invention consists, first, in providing the flanging-head shaft with a tapering sleeve secured at its base, and having an annular 45 rim or flange, around which sleeve and by means of which rim the flanging-head is supported; second, in combining with this sleeve, or the flanging-head supported on the shaft, a stationary guide-pin secured to the base of 50 the machine and extending up within the sleeve or head to guide its movement in flanging; third, in forming the flanging-head of a

curved or conoidal shape, so that it will press against a greater portion of the surface to be flanged, and so bend it up without tearing, and 55 afterward press the flange thus bent up firmly against the annular former; fourth, in providing the flanging-head with a series of pressing-faces extending diagonally across its upper surface to enable it to expand the metal 60 of the flange more easily; and, finally, in details of construction hereinafter specifically set forth.

To enable others skilled in the art to make and use my invention, I will describe its construction and operation.

In the drawings referred to, A represents the base of my improved flanging-machine; B B, the standards, and C the top brace. Secured to the base A is the table D, on which 70 the plate to be flanged is supported. Above the table D is the cage E, having the top ring, e, and to which, at the base, is bolted or otherwise removably secured the annular former f, the inner surface of the former acting as the anvil or seat against which the flange of the metal plate is pressed. These 75 parts are of the ordinary construction.

The flanging-head shaft G is provided at its base with a sleeve, h, which is screwed or otherwise secured thereon, the sleeve being tapering in form, and having the annular rim or flange h', around which tapering sleeve and on which rim the flanging-head K is supported by means of its hub k. The flanging-head is 85 curved or conoidal in form, the upper part being formed in a gradual curve, which gradually fades at the greatest diameter until it is straight or tapering slightly downward. By 90 this construction the head is adapted to expand and bend over the flange more easily and truly, the upper curved portion enabling the head to press against a greater portion of the metal to be flanged, and so spread it without excessive tearing strain thereon, and the curved 95 surface of the head still giving a large bearing-surface on the flange as it is bent over until it is pressed tightly against the inner surface of the annular former f by the straight portion of the head. The flanging-head K is provided 100 with a series of pressing-faces, l, extending diagonally across its upper surface, and separated by depressions or grooves extending in the same direction, these diagonally-extending

pressing-faces serving still further to prevent the tearing of the metal spread in forming the flange by imparting a diagonal pressing-strain thereto instead of a direct upward strain, which 5 might tear the plate and render it useless. The faces *l* extend only part way down the surface of the head, the depressions between them fading away before they reach its largest diameter, so that when the head is drawn 10 through the metal plate and presses the flange formed thereby against the annular former *f* it presents a smooth surface the full size of the inner diameter of the flange. The flanging-head may be made entirely of cast-iron, or 15 may be made in two parts, its body *m* being cast, and having a ring or flange around its base, on which is supported a hardened-steel ring, *n*. This latter construction is preferred, as it gives a hardened face to the head at the 20 point subjected to the hardest wear, and permits the use of the same head for different sizes of flanges by changing the rings, which are made of different thicknesses and are interchangeable on the same head, so that the 25 same body, *m*, can be employed in forming several sizes of flue-holes. The flanging-heads are provided with hubs *k*, which are all made of proper size to fit the sleeve *h*, and are made hollow to lighten them, very large heads being 30 braced, as at *k'*, to enable them to withstand the strain brought upon them. The flanging-heads may either be circular, as shown, or of any irregular shape desired, such as that shown in Fig. 4 for flanging flue-holes of irregular shape, or that shown in Fig. 5 for flanging man-holes and hand-holes, annular formers or anvils of a shape corresponding to these heads 35 being of course employed with them.

The table *D* has an annular recess or opening, *d*, in the center thereof, and extending up in the center of this recess is the guide-pin *a*, which is rigidly secured to the base *A* of the frame, and extends up within the sleeve *h*, or within the flanging-head, if no sleeve is employed, the pin serving to retain the flanging-head in proper position, and to prevent any sidewise movement as it is raised to form the flange.

Mounted in the top brace, *C*, in the same 50 axial line with the guide-pin *a*, is the power-shaft *P*, which is connected to the bevel cog-wheel *S*, above the top brace, by means of a feather, *p*. At the base of the shaft *P* is rigidly secured the tubular extension *R*, which 55 carries within its lower end the nut *r*, and this nut screws onto the threaded end *g* of the shaft *G*, and thus raises the shaft and flanging-head carried on it through the former *f*, without rotating the flanging-head, the end of 60 the tubular extension pressing against the top ring, *e*, of the cage, and the shaft *G* rising within the tubular extension.

Instead of the tubular extension *R*, the nut *r* may be connected to the power-shaft by 65 means of bars bolted to each, the only requisite being that a space is left between the nut and power-shaft, within which the threaded

end of the shaft *G* may enter as the nut turns on it and raises the flanging-head.

Power is applied to the shaft *P* from the 70 power-belts *T* *T'* through the cog-shaft *s* and bevel-cog *s'*, which meshes into the cog-wheel *S*, and thus turns the shaft. The cog-shaft *s* is provided with the tight pulley *t* and with two loose pulleys, *t'* *t''*, the power-belts *T* *T'* 75 passing around the loose pulleys when the machine is not in operation, and one or the other belt being thrown onto the tight pulley, according to the direction in which it is desired to rotate the power-shaft in screwing or 80 unscrewing the nut *r* on or off the shaft *G*. At the top of the power-shaft *P* is the swivel *u*, which is connected at one end with the lever *U*, pivoted in the upright *c*, and at the other end to the hand-bar *u'*, by means of 85 which the power-shaft is raised and lowered, as hereinafter described.

My improved flanging-machine operates in the following manner: The flanging-head *K* is placed within the recess *d* of the table *D*, 90 over the stationary guide-pin *a*, the shaft *G* extending above the table. The plate with the circular hole cut therein is brought to the proper heat, passed over the shaft, and placed on the table. The cage *E* is then placed on 95 the plate, the shaft *G* extending through the ring *e* of the cage. By means of the hand-bar *u'* the shaft *P*, with its tubular extension *R*, is lowered until the nut *r* fits over the end of the shaft *G*, and the belt *T* is then thrown 100 onto the pulley *t*, thus causing the rotation of the power-shaft, and causing the nut *r* to screw onto the shaft *G*, and thus raise the shaft and flanging-head without rotating them. The cage *E* is prevented from turning by means 105 of the hook *w*, connecting it with one of the standards. As the tubular end of the power-shaft presses down against the cage, and at the same time draws the shaft *G* through the cage, the cage is pressed down on and holds the 110 plate firmly, and the nut gradually draws the flanging-head through the hole in the plate, causing it to press the metal that is to form the flange against the annular former or anvil *f* at the base of the cage and form the flange 115 around the hole, and finally draws the flanging-head entirely through the plate. On account of the curved or conoidal form of the flanging-head, it presses against a greater surface of the plate to be flanged, not only at one 120 point in its bend, but during the entire operation of flanging, and for this reason is enabled to form the flange without any great tearing-strain on the edge of the plate, and finally to press the flange tightly against the annular 125 former, and so form a more truly bent flange. The diagonally-extending pressing-faces on the upper part of the head serve to press the metal of the flange only at different points around its edge, and to travel slightly around the edge 130 as the non-rotating head is drawn through, giving a diagonal pressing effect to the head during the first part of the operation, while it has the direct drawing-strain, and is the full

size of the opening to be formed at the lower part of the head, and is thus enabled to press the flange against the annular former around its entire surface at one time. The stationary

5 guide-pin *a* holds the head from sidewise movement, so that if the plate is placed properly on the table the flange is formed the same width entirely around the hole. After the flange is formed the operator throws the belt *T* off the fixed pulley onto its loose pulley, and throws the belt *T'* onto the fixed pulley, thus causing the rotation of the power-shaft in the opposite direction, so that the nut *r* unscrews from the shaft *G*. It is then drawn up out of the way

10 by the hand-bar *u'*, and the cage and flanging-head are lifted off, when the flanged plate may be removed, after which the flanging-head is again placed over the stationary guide-pin, and the machine is ready to form another flange.

15 To form a flanged hole of another diameter an annular former of the proper size is secured to the cage, and another flanging-head placed over the sleeve *h*; or another ring of different thickness is placed around the head, this latter course being generally pursued where the diameter of the hole to be flanged differs but slightly from that previously flanged. If the ring around the head breaks or becomes scored or worn out, it can be easily replaced, and thus 20 greatly extend the duration of the flanging-head.

To form flanges on irregularly-shaped holes—such as boiler-flues or man-holes having the shapes of the flanging-heads shown in Figs. 35 4 and 5 of the drawings—the heads are placed over the sleeve *h*, and correspondingly-shaped formers secured to the cage, and the machine operated as above set forth. I am enabled to flange holes of these irregular shapes by the 40 use of the stationary guide-pin *a*, fitting within the flanging-head or its sleeve, as the unequal strain on the different parts of the flanging-head would throw it out of true line were it not held from side motion by the guide-pin.

45 What I claim as my invention, and desire to secure by Letters Patent, is—

1. In flanging-machines of the class specified, the combination of the shaft *G*, carrying

the tapering sleeve *h*, and flanging-head *K*, fitting around and supported on said tapering 50 sleeve, substantially as and for the purposes set forth.

2. In flanging-machines of the class specified, the combination of the shaft *G*, carrying the tapering sleeve *h*, having the annular rim *h'* at its base, and the flanging-head *K*, having a hub fitting around and supported on the tapering sleeve and its rim, substantially as and for the purposes set forth.

3. In flanging-machines of the class specified, the combination of the non-rotating flanging-head, the shaft for raising the flanging-head, and the stationary guide-pin extending within the flanging-head to guide its movement in flanging, substantially as set forth. 60

4. In flanging-machines of the class specified, the combination of the shaft carrying the sleeve, the flanging-head supported around the sleeve, and the stationary guide-pin extending within the sleeve, substantially as and 70 for the purposes set forth.

5. In flanging-machines of the class specified, the non-rotating flanging-head having a series of pressing-faces extending diagonally across its upper surface, substantially as and 75 for the purposes set forth.

6. In flanging-machines, the flanging-head formed of the body *m*, and removable and interchangeable rings *n*, substantially as and for the purposes set forth.

7. In flanging-machines, the combination, with the shaft *G*, carrying the non-rotating flanging-head *K*, and the cage *E*, having the annular former at its base, of the rotary power-shaft *P*, having the tubular or equivalent 85 extension *R*, and nut *r*, supported at the base of the extension, said nut being adapted to screw onto or off the shaft *G* on the rotating of the power-shaft, substantially as and for the purposes set forth.

In testimony whereof I, the said ALFRED WILBUR, have hereunto set my hand.

ALFRED WILBUR.
